UNITED STATES PATENT OFFICE.

LUCIEN PAUL BOUR, OF PARIS, FRANCE.

SAFETY-FASTENING FOR HAIR-SLIDES.

1,354,236.

Specification of Letters Patent. Patented Sept. 28, 1920.

Application filed September 20, 1919. Serial No. 325,151.

To all whom it may concern:

Be it known that I, LUCIEN PAUL BOUR, a citizen of the French Republic, residing at Paris, France, (whose post-office address is 5 Rue Robineau No. 1,) have invented certain new and useful Improvements in Safety-Fastenings for Hair-Slides, of which the following is a specification.

The present invention relates to hair slides 10 of the kind comprising for fixing purposes, a double pin pivoted at one end on the slide and engaging at the other end with a retaining device, the fixing being effected by clasping a tuft of hair between the slide and the 15 pin.

The present invention consists in a type of closure in which the movement of the element which effects the hooking and unhooking is made parallel to the slide and in 20 which said movable element is held in its closed position by the spring which is ordinarily interposed between the slide and the pin on which bears the tuft of hair caught. The result of this arrangement is that the 25 hair slide or barrette can not be opened by accidental pull which generally takes place in a direction perpendicular to the barrette, and that it will be retained the better as the mass of hair caught up is greater.

One particularly advantageous mode of 30 construction is hereinafter described by way of example, and is illustrated in the accompanying drawings.

In this mode of construction the pivot of 35 the pin is fixed on the slide, and the retaining hook is arranged so as to be capable of oscillating around an axle, being maintained in the fixed position by a spring blade which runs in the same direction as the slide and is 40 pivoted at one end on a heel of the hook and slidingly guided at its other end in a suitable path.

In the drawings:

Figure 1 shows a sectional elevation, and 45 Fig. 2 a plan view of the fastening device constructed according to the present invention.

The slide is provided at one end with 50 ears 2, at the upper part of which is pivoted a pin 3 and at the other end with a flat hook 4 which is capable of oscillating and is provided with a head 14 being pivoted on an axle 5, which is maintained in a fold of the slide. The pin 3 has two branches (see Fig. 55 2) which join together at 12 and are con-

tinued by a buckle 13. A spring blade 7 is pivoted at one end on an axle 8 carried on a heel 9 of the hook 4 and placed nearer the middle of the pin than the pivot 5. The other end 10 of the spring blade 7 has approximately the same curvature as the slide 1 and engages in guides 11 which have also the same curvature as the slide 1 and are formed by a folding of the basis of the ears 2. Owing to this arrangement the end 10 60 of the spring blade is capable of sliding when it is brought back toward the slide 1, and in all positions its end which pivots on the axle 8 is forced toward the slide, thereby always bringing the hook 4 into its hooking 65 position. The slide 1 is provided with ribs 15 for increasing its rigidity and preventing its deformation.

The working of the slide is as follows:

The slide being closed, its opening is effected by pressing with the finger the head 14 of the hook to the right and by raising the end 13 of the pin 3 so as to liberate the cross-member 12 from the projection of the hook 4. In order to fix the hair slide, a tuft of hair is clasped between the pin 3 and the spring blade 7, and a pressure is exerted on the end of the pin 3 in order to force it back toward the slide; in this movement the cross-piece 12 meets the inclined face of 75 the projection of the hook 4 and causes the latter to tip to the right. When the cross-piece 12 is released by the end of the projection of the hook 4, the spring 7 presses upon the heel 9 and the hook 4 is automatically brought into the fixing position. When the pin is thus engaged under the retaining hook, the action of the spring-blade 7 upon the heel 9 retains it with a force 80 which is the greater, the larger the size of 85 the tuft of hair.

It is to be understood that the mode of construction which has just been described is given only by way of example and that it is possible to effect many modifications 100 without departing from the spirit of the invention.

What I claim is:—

1. A fastening device for hair slides comprising a slide, a pin pivoted to one end 105 of said slide, a pin retaining device at the other end of the slide and movable longitudinally with respect to the slide, and a plate spring having its ends connected to the slide and retaining device and serving 110

to simultaneously lock the hair against the pin and to maintain the retaining device in a closed position with respect to the pin.

2. A fastening device for hair slides comprising a slide, a pin pivoted at one end of said slide, a retaining hook for said pin pivoted at the other end of the slide and moving parallel with said slide, a head on said hook, and a plate spring serving at the same time to hold the hair against the pin and to act by its end on the head of the retaining hook to hold it fastened.

3. A fastening device for hair slides com-

prising a base provided at one end with a slide, a pin pivoted to said end, a retaining hook for said pin pivoted to the other end of said base and moving parallel to said base, a head provided with an axis on said hook, and a plate spring for holding the hair against the pin and pivoted at one end on said axis and guided at the other end in the slide of said base.

In testimony whereof I have signed my name to this specification.

LUCIEN PAUL BOUR.
